Inventor:
Charles R. Welsh,

by Joseph W. Harris
Atty.

UNITED STATES PATENT OFFICE.

CHARLES R. WELSH, OF SCHOFIELD BARRACKS, TERRITORY OF HAWAII.

SHOULDER-PATCH-INSIGNIA-ATTACHING MECHANISM.

Application filed October 6, 1923. Serial No. 667,031.

To all whom it may concern:

Be it known that I, CHARLES R. WELSH, a citizen of the United States, and residing at Schofield Barracks, Territory of Hawaii, in the county of Oahu, have invented certain new and useful Improvements in Shoulder-Patch-Insignia-Attaching Mechanism, of which the following is a specification.

This invention relates to improvements in shoulder patch insignia attaching mechanism, such for example, as are worn on uniforms of soldiers, sailors, etc., and also, may be used to attach badges, chevrons, and other insignia of rank.

15 An object of the invention is to provide a means that permits the easy and quick attaching of the insignia;

20 A further object is to provide a cheap, durable device that will not soil or disfigure the uniform;

25 A further object is to provide a mechanism that is invisible, that will hold the insignia permanently in shape, and always present a neat appearance.

30 A further object is to provide a means that will keep the edges of the patch close to the fabric of the uniform;

Other objects will appear upon reading the specification.

35 In the accompanying drawings,

Figure 1 is a front view of one design of shoulder patch secured to a sleeve of a uniform;

40 Fig. 2 represents a section of a sleeve of a coat or blouse of a uniform, with a button-hole therein, to receive the tongue of the shoulder patch;

Fig. 3 is a rear view of the front part of the patch;

45 Fig. 4 is a vertical section of the patch, on the line 4—4 of Fig. 3, showing its "dished" shape, and the protruding tongue;

Fig. 5 is a vertical section of the patch on the sleeve, showing the front and rear members, and the cloth of the uniform engaged between them, the two members being under tension;

50 Fig. 6 is a plan view of the cooperating member or spring back, showing an opening through which the tongue projects, and also the depressions in which the wings of the tongue rest; also the sectors of the spring back which provide the necessary resilience to firmly engage the cloth of the uniform;

Fig. 7 is a longitudinal section of the spring back, on the line 7—7 of Fig. 6, showing the depressed portions which receive the wings of the tongue, and the finger grips by which the back is manipulated; and

Figs. 8 and 9 are a plan and longitudinal section, respectively, of a modified cooperating member, or spring back, Fig. 9 being a section on the line 9—9 of Fig. 8.

In Fig. 1, the shoulder patch is shown as a disk with a border, and a leaf in the center. The disk may have any desired shape. The invention may be applied to any of the designs and identification marks, or shapes of shoulder straps, and of insignia of all types generally, and also, to all types of badges, etc.

A support member, or dished plate 1, which may be of metal, and may be resilient, or may be of stiff celluloid or similar material, Figs. 3 and 4, is provided with one or more projecting tongues 2, symmetrically located, and which may be stamped and bent up out of the stock of the metal 1, or may be riveted or soldered thereto. The tongue is provided with wings or ears 3, which will be further referred to hereafter. In its preferred form, the length of the tongue under the wings is less than the depth of the dished plate. On the outer face of the metal plate 1 is suitably attached the design of the shoulder patch 4, which may be of cloth, or metal, etc., and which may be attached in any preferred manner. Generally, the patch is sewed on, but it may be cemented with water-proof glue, if desired.

The cooperating member, or spring back 5, consists of a disk having preferably a size corresponding generally to that of the plate 1, and is preferably made of spring metal, stiff celluloid, or other resilient material. It is generally flat, as shown in Fig. 7, with slightly curved edges 6, and has a plurality of slots 7, cut preferably radially therein. The sectors 8 are thereby given flexibility, or resilience, which provides for firmly engaging the dished plate 1. In the center of the spring back is an opening 9, having extensions 10, which permit the wings 3 of the tongue 2 to pass; at the other edge of the spring 9 are depressions 11 in the spring back, into which the wings 3 rest, and are then locked against accidental movement.

when the two parts of the patch have been connected. The spring back is also provided with finger grips 12, by which it is moved into and out of engagement with the 5 tongue 2. The outer edge of the spring back either substantially coincides with that of the dished plate, or is overlapped and enveloped thereby.

In assembling the patch upon the garment, the tongue 2 is passed through the button-hole 13, Fig. 2, in the cloth 14, and through the opening 9 and extensions 10 in the spring back 5, the latter is now depressed until the wings 3 are entirely through the 15 extensions 10, and while depressed, slid forward until the wings 3 rest in the depressions 11, after which the pressure upon the spring back is released, whereupon the two parts are firmly engaged and held together 20 under tension, and cooperate to securely hold the sleeve of the garment between them.

To remove the patch, the spring back 5 is depressed until the wings 3 are free from the depressions 11, and is then slid over until the wings 3 are in position to pass 25 through extensions 10 and opening 9. The spring back may then be removed and the dished plate 1 with its tongue 2 removed from the garment.

In Figs. 8 and 9, a modified spring back 15 is provided with a central opening 19, and extensions 20 through which the tongue 2 and wings 3 may pass. There are also provided suitable depressions 21, into which 30 the wings 3 may rest, and finger grips 22, by which the back is operated. To assemble this modification, the back is placed over the tongue 2 of the dished plate 1, and depressed until the wings 3 pass through extensions 40 20; the back is then given a sliding twist or turn, so that the wings 3 will slip into the depressions 21, upon which the two parts will be securely engaged. To disengage the parts, the back is depressed until the wings 45 3 are free from depressions 21, and is then twisted until the wings are over the extensions 20; the pressure is then released and the parts separated.

The assembled shoulder patch holds the 50 face thereof close to the garment, and since the outer edges, or circumference, of each part substantially coincide, or that of the dished plate overlaps that of the spring back, and since the spring back is resilient, 55 the edges of the patch are retained in close contact with the fabric of the garment, presenting a neat and pleasing appearance.

I claim:

1. A shoulder patch comprising a support 60 member for the identification mark, a cooperating member, one of said members being resilient, an engaging tongue secured to one of said members, and means on the other member to engage and securely hold said 65 tongue.

2. A shoulder patch comprising a support member for the identification mark, a cooperating member of approximately the same size as the support member, one of said members being resilient, an engaging tongue 70 secured to the support member, and means on the cooperating member to engage and securely hold said tongue.

3. A shoulder patch comprising a support member for the identification mark, a cooperating member of approximately the same size as the support member, one of said members being resilient, the edges of the two members substantially coinciding, means 75 secured to one member to cooperate with means on the other member to firmly engage and securely hold the two members together. 80

4. A shoulder patch comprising a support member for the identification mark, a cooperating member of approximately the same size as the support member, one of said members being resilient, the edges of the two members substantially coinciding, an engaging tongue secured to the support member, means upon the cooperating member to engage and securely hold the tongue and the 85 two members under tension.

5. A shoulder patch comprising a support member for the identification mark, a cooperating member of approximately the same size as the support member, one of said members being resilient, the edges of the two members substantially coinciding, an engaging means secured to the support member, means on the cooperating member 90 to interlock with the engaging means on the support member and hold the two members together under tension. 100

6. A shoulder patch comprising a support member for the identification mark, a 105 cooperating member of approximately the same size as the support member, the cooperating member provided with resilient portions, an engaging tongue secured to the support member, means upon the cooperating member to engage and securely hold said tongue. 110

7. A shoulder patch comprising a support member for the identification mark, a cooperating member of approximately the same size as the support member, the cooperating member provided with resilient portions, the outer edges of the two members substantially coinciding, an engaging tongue secured to the support member, wings upon said tongue, and means on said cooperating member to receive said tongue and engage said wings. 120

8. A shoulder patch comprising a dished support member for the identification mark, a 125 cooperating member of approximately the same size as the support member, the cooperating member provided with resilient sectors and having a curved-up edge, the outer edges of the two members substantially co- 130

- inciding, an engaging tongue secured to the support member, wings upon said tongue, means on said cooperating member to receive said tongue and engage said wings, and
- 5 finger grips on said cooperating member to facilitate the assembly of the complete shoulder patch.
9. A shoulder patch comprising a dished support member for the identification mark,
- 10 a cooperating member of approximately the same size as the support member, the cooperating member provided with resilient sectors and having a curved up edge, the outer edges of the two members substantially co-
- 15 inciding, an engaging tongue secured to the support member, wings upon said tongue, means on the cooperating member to receive said tongue and engage said wings, said

tongue having a length below its wings less than the depth of the dished member.

10. A shoulder patch comprising a dished support member for the identification mark, a cooperating member of approximately the same size as the support member, the cooperating member provided with resilient sectors and having a curved-up edge, the outer edges of the two members substantially co-inciding, an engaging tongue secured to the support member, wings upon the tongue, depressions on said cooperating member to receive and engage said wings, the length of the tongue under the wings being less than the depth of the dished member.

In testimony whereof I affix my signature.

CHARLES R. WELSH.
